UNITED STATES PATENT OFFICE.

DE WITT C. BOWEN, OF KANSAS CITY, MISSOURI.

DESIGN FOR A BRACKET.

SPECIFICATION forming part of Design No. 24,967, dated December 10, 1895.

Application filed October 11, 1895. Serial No. 565,415. Term of patent 7 years.

To all whom it may concern:

Be it known that I, DE WITT C. BOWEN, of Kansas City, in the county of Jackson and State of Missouri, have invented and produced a new and original Design for a Bracket, of which the following is a full, clear, and exact description.

Reference is to be had to the accompanying drawing, forming a part of this specification, which represents a perspective view of a bracket embodying my new design.

The leading feature of my design resides in the bracket having an upright member and a curved member having its convexed side joining the upright member at about the cen-

ter and diverging in curved lines from such point.

Other features of the design reside in the flat broadened surfaces at the ends of the upright and curved members, and the pendent arm at the lower end and at one side of the upright member.

I claim—

The design for a bracket herein shown and described.

DE WITT C. BOWEN.
